UNITED STATES PATENT OFFICE.

JOHN D. TAYLOR, OF PIKETON, OHIO.

ELECTRIC RAILWAY BLOCK-SIGNAL.

SPECIFICATION forming part of Letters Patent No. 450,646, dated April 21, 1891.

Application filed September 9, 1890. Serial No. 364,474. (No model.)

To all whom it may concern:

Be it known that I, JOHN D. TAYLOR, of Piketon, in the county of Pike and State of Ohio, have invented a new and Improved 5 Electric Railway Block-Signal, of which the following is a specification, reference being had to the annexed drawings, forming a part thereof, in which—

Figure 1 is a plan view of the signal-transmitting mechanism. Fig. 2 is a side elevation of the electric motor and its connections. Figs. 3, 4, and 5 are detail views of the circuit-breaking wheels. Fig. 6 is a perspective view of the track-instrument. Fig. 7 is a side elevation of the semaphore and its levers. Fig. 15 8 is a diagrammatic view including the receiving-instrument in the dispatcher's office and a switch and battery. Fig. 9 is a front elevation of the dial.

Similar letters and figures of reference indicate corresponding parts in all the views.

The object of my invention is to place the control of trains on any system of blocks in the hands of one man, who will have an efficient 25 means of knowing the exact location of all trains, and consequently will know just what signals to give to following trains.

My object is also, further, to provide a danger-signal that will be automatic and will 30 be set to show "danger," and also report to the block-dispatcher that the train has passed that point; also, to provide a signal which when once set to the "danger" position cannot be changed except by the block-dispatcher.

My invention is designed to avoid the errors made by incompetent operators and to reduce the cost of operating the block signaling system.

In carrying out my invention I furnish the current for operating the system from a battery or dynamo at the block-dispatcher's office. The intermediate stations on the road are provided with the apparatus shown in 45 Figs. 1 to 7, inclusive, while the terminal stations are provided with the apparatus represented in Figs. 8 and 9.

In the instrument for the intermediate stations the shaft A, which is journaled in the standards B, carries the worm-wheel C and the break-wheels D E F. The periphery of

the break-wheel D is divided into three parts, each of which is grooved transversely and the grooves filled with insulating material, so as to form a transmitting-surface. One of the divisions represents the word "red" according to the Morse code, another "green," another "white." The wheel E is provided with three insulating-pieces g r w, inserted at equidistant points, and the wheel F is furnished with one such insulating-piece r'. Contact-springs d e f are arranged to contact, respectively, with the wheels D E F. Upon the shaft A is mounted a crank G, which is arranged to operate the visible signal or semaphore, as will presently be described. The worm-wheel C is engaged by the worm H on the shaft I'. The said shaft I' is journaled in suitable standards. Upon one end of the shaft I' is mounted a crank J, provided with a crank-pin j.

The motor M, by which the signaling mechanism is operated, is provided with an armature-shaft M', which is axially in line with the shaft I', and which carries a crank K, provided with a crank-pin k, which corresponds to the crank J on the shaft I'. The armature-shaft M' is capable of longitudinal movement, and is provided with an auxiliary disk-armature I, which is within the influence of the field-magnet of the motor, so that when a current is sent through the motor the said disk-armature is drawn forward toward the field-magnet of the motor, thereby causing the crank K to overlap, and thereby engage the crank J, and causing the worm-wheel C to revolve. The movement of the armature-shaft in the direction indicated is opposed by a spiral spring k', so that when the disk-armature ceases to be attracted by the field-magnet of the motor the spring k' will return the armature-shaft to its former position and disconnect the crank K from the crank J.

At the intermediate station is located a polarized relay R and an ordinary direct-current relay R'. The circuit is from the main line to the spring d, thence through the circuit-breaking wheel D, through the contact-spring d', pressing against the side of the wheel, through the polarized relay R, thence to the earth, or on to the next station.

The local battery B' is connected by the

wire 1 with one binding-post of the motor M. The other binding-post of the motor is connected by the wire 2 with the forward contact of the relay R, and the arm L of the relay is connected by the wire 3 with the remaining pole of the battery. The same pole of the battery is connected by the wire 6 with the contact-springs 5 10, which press the sides of the break-wheels E F. The contact-spring e of the wheel E is connected by the wire 4 with the wire 2, which enters one of the binding-posts of the motor. The spring f is connected by the 9 with the lever Q of the track-instrument presently to be described. The same lever Q is also connected by the wire 8 with the armature-lever of the relay R', and the forward contact P of the said relay is connected by the wire 7 with the wire 2, entering one of the binding-posts of the motor. The contact-spring S of the track-instrument is connected by the wire 13 with one terminal of the magnet of the relay R', and the remaining terminal of the said magnet is connected by the wire 11 with the wire 1.

25 The apparatus shown in Fig. 1 is placed in a box on the semaphore-post, and the crank G, carried by the shaft A, is connected by a rod A' with the arm Y of the semaphore Z. The said crank G and the arm Y are proportioned so that when the shaft A makes one revolution it moves the arm Y, through the medium of the crank G and rod A', through about one-quarter of a revolution. The motor mechanism being arranged to stop at three different points in the revolution of the shaft A, the semaphore-arm Y may be placed in three different positions, as shown in Fig. 7, viz: horizontal, as shown in full lines, inclined at an angle of about forty-five degrees, as shown in dotted lines at Z', and dropped into a vertical position parallel with the semaphore-post, as shown at Z².

The track-instrument, the contact-springs of which are represented diagrammatically in Fig. 1, is shown in perspective in Fig. 6. It is formed of a shaft X, journaled in supports attached to the extended portion of a tie, the said shaft carrying at the end adjoining the track-rail a curved lever V, which is pressed upwardly by a leaf-spring W, so as to lie normally within the path of the wheels of the train. The outer end of the shaft X is provided with an arm U, which is connected by the rod T with the lever Q, the said lever being pivoted in the standard Q'. In the path of the free end of the lever Q is supported a contact-spring S, and the lever Q and spring S are arranged in the electric circuit, as described in connection with Fig. 1.

60 At the terminal station is arranged an instrument B², provided with an electro-magnet B³ and an armature lever B⁴, furnished at its shorter end with a retractile spring a' and carrying at its free end a spring-pressed pawl a. The said pawl a is arranged to act upon the ratchet-wheel c, mounted on the shaft c', and the ratchet-wheel is prevented

from retrograde motion by the spring-actuated click b. The movement of the armature-lever B⁴ is limited by means of adjusting-screws in the same manner as in the case of an ordinary telegraph-sounder, so that the pawl will carry the ratchet-wheel only one notch at a time. Upon the shaft c' is mounted the index i', which revolves in front of the dial h', said dial having upon it the words "Red," "Green," and "White," or red, green, and white segments. One terminal of the magnet B³ is connected with the main line. The other terminal is connected through the arm m with the double switch C'. The arm n of the said switch is connected with the ground-wire. The two arms m n are pivoted to the ends of an insulating-bar q, which is furnished with a handle p, by which the switch is operated. The arm m is capable of contacting with the points Cu' and Zn, and the arm n is capable of contacting with the points Zn' and Cu. The points Cu' and Cu are connected electrically with the positive pole of the battery B.

65 My improved signal is designed to be used only where all trains run in the same direction on the same track, and to describe the method of operation I will suppose them in use at a series of stations and will describe the operation at station No. 1. When a train passes station No. 1, it sets the semaphore at that place in the "danger" position and notifies the block-dispatcher that the train has passed that point. When the train passes station No. 2, it produces the same result at that place. For the sake of brevity I will use the word "red" to denote the position of the semaphore for indicating "danger," the word "green" to denote the position indicating that a train may proceed with caution, and the word "white" to denote the position indicating "safety." When the block-dispatcher is notified that the train has passed station No. 2, it will be his duty to set the target at station No. 1 to show "green." This he will do by bringing the levers m n of the switch shown in Fig. 8 into contact with the points Cu' and Zn'. This causes a positive current to flow to the line through the polarized relay R (shown in Fig. 1) and throws the arm L against the contact-point N. The current from the battery B' then flows through wire 1, the motor M, wire 2, the contact of the arm L, and the wire 3 back to the battery B', energizing the motor, and causing its armature to revolve in the direction indicated by the arrow. The attraction of the armature I by the field-magnet in the manner described causes the armature-shaft to move longitudinally, bringing the pins k and j into engagement with each other, causing the worm H to rotate, and the said worm causes the wheel C, the break-wheels D, E, and F, and the crank G to rotate in the direction indicated by the arrows. As before mentioned, the wheel D, passing under the contact-spring d, causes makes and breaks in the main-line circuit,

which spell the word "red" in passing over one third of the circumference, "green" in passing over another third, and "white" in passing over the remaining portion. Spaces between the words are left so that the contact-spring *d* touches the conducting material of the wheel *D* when the wheel comes to rest and the semaphore assumes either of its three positions. As soon as the spring *d* leaves the 5 conducting material and rests upon one of the insulating-pieces before the commencement of either of the words, as is indicated by the click of the lever of the instrument *B*², (shown in Fig. 8,) the operator shifts the 10 switch *C*' to its normal position—that is to say, he brings the levers *m* and *n* into contact with the points *Zn* and *Cu*, respectively. This 15 sends a negative current into the line, and the arm *L* of the polarized relay *R* is thrown against the insulating back-stop, thus breaking the 20 circuit of the battery *B*'. Before this takes place the contact-spring *e* has left the insulating-bar *r* in the wheel *E* and comes into contact with the conducting portion of the 25 wheel, so that the circuit of the battery *B*' is closed through the wire 1, motor *M*, wire 4, contact-spring *e*, wheel *E*, and wires 5 and 6, back to the battery *B*'. The motor continues 30 in the circuit until the insulating-piece *g* in the wheel *E* is brought under the contact-spring *e*. When this occurs, the current through the motor is interrupted, the field-magnet loses its power of attracting the disk-armature *I*, and the armature-shaft is moved 35 longitudinally by the spring *k*', so that the clutch is disengaged and the worm *H* stops. The one-third revolution of the shaft *A* gives to the crank *G* the position shown at *G*' in Fig. 7, causing the arm *Y* to take the position indicated by *Y*', bringing the semaphore-arm into the inclined position shown in dotted lines and indicated by *Z*'. While the break-wheel *D* is making its third of a revolution it makes and breaks electric contact with the 40 spring *d*, so as to send impulses over the line corresponding to the word "green." Each impulse causes the lever *B*⁴ of the instrument *B*² to make a stroke. This lever, acting through the pawl *a*, moves the ratchet-wheel 45 *c* forward one tooth for each impulse. While the lever *B*⁴ acts as a sounder-lever, spelling out the word "green," the pawl *a*, by acting on the ratchet-wheel *c*, turns the shaft *c*', so as to cause the index *i*' to point to the word 50 "green," or to the green-colored portion of the dial. Arranged in this way the audible and visible signals verify each other. When the train has reached station No. 3, the dispatcher will set the signal at station No. 1 to show 55 "white." The operation in this case is precisely like that described before. The crank *G* takes the position indicated by *G*² in Fig. 7, and the semaphore-arm *Z* is dropped into a vertical position, thus showing "safety." At the same 60 time the operator will set the semaphore at station No. 2 to show "green." This is done in the same manner as before described, each

semaphore having a switch and instrument *B*² corresponding to it in the dispatcher's office.

To explain the manner in which a passing train sets the semaphore to indicate "danger," I will suppose that a second train passes station No. 1, and while the semaphore shows "white." When the semaphore shows "white," the contact-spring *f* rests on the portion of the wheel *F* which is marked *w*. The wheel *F* has only one piece of insulating material in its periphery, and this piece is arranged to come under the contact-spring *f* when the semaphore shows "red." In other positions of the semaphore the springs *f* in the metallic portion of the wheel *F* are in electrical contact. When the lever *V* of the track-instrument is pressed by the wheels of a train, the shaft *X* is rocked and the lever *Q* will be brought into contact with the spring *S*, when the current from the battery *B*' will flow through the wires 1 and 11, relay *R*', wires 12 13, spring *S*, lever *Q*, wire 9, contact-spring *f*, wheel *F*, and wires 10 and 6, back to the battery. This energizes the relay *R*', bringing its armature-lever *O* against the contact *P* and closing the circuit of the battery *B*' through two channels, the first through the wires 1 11, the relay *R*', wires 12 14, contact *P*, armature-lever *O*, wires 8 9, contact-spring *f*, the wheel *F*, and wires 10 and 6, back to the battery *B*'. The resistance of the relay *R*' is comparatively high, so that the current through the motor *M* is not materially diminished by being arranged in parallel with it. The current through the latter circuit energizes the motor *M*, causing it to turn the wheels *C D E F* and the crank *G*, as before described, and they continue to turn until the insulating-piece *r* in the wheel *F* is brought under the contact-spring *f*, when the circuit through the relay *R*' and the motor *M* is broken and the motor stops, as before described. The armature-lever *O* of the relay *R*' also falls against the back-stop. The position of the semaphore-arm under these circumstances indicates "danger," as the crank *G* has moved from the position *G*' to that indicated by *G* and the semaphore-arm from *Z*² to *Z*. Any further contact of the lever *Q* with the spring *S* will produce no effect, as the circuit is broken between the spring *f* and the wheel *F*, so that by this arrangement it does not matter how long or how short a time the train occupies in passing over the lever *V* the semaphore will go to "red" and stop there. By the movement of the wheel *D* an impulse 125 has been sent over the line and through the instrument *B*², which corresponds with the word "red." At the same time the index *i*' is set so as to point to red, thus notifying the

- dispatcher that a train has passed that station. The same operation would have been performed and the same effect produced had the train entered the station while the semaphore showed "green," except that the wheels C, D, E, and F and the crank G would have made two-thirds of a revolution instead of one-third, the wheel F would have traveled under the contact-spring *f* from *g* past *w* to *r*, the semaphore-arm would have gone from "green" to "white" and then to "red," the contact-spring *d* would have passed over the words "white" and "red," and the index *i'* from "green" past "white" to "red."
- 15 Having thus described my invention, I claim as new and desire to secure by Letters Patent—
1. In an electric railway block-signal, the combination of the semaphore, the semaphore-operating motor, the break-wheels operated by the said motor, the polarized relay, the plain relay, the track-instrument, and the electrical connections, substantially as specified.
  2. In an electric railway block-signal, the combination of the semaphore, the semaphore-operating motor, the break-wheels operated by the said motor, the polarized relay, the plain relay, the track-instrument, the electrical connections, and a pole-changing switch and indicator at the terminal station, substantially as specified.
  3. In an electric railway block-signal, the combination, with the semaphore, the crank-shaft for operating it, the break-wheel *F*, mounted on said shaft, and a spring *f*, pressing on the wheel, of the track-instrument, the polarized and plain relays *R* *R'*, an electric motor and gearing which connects it with the crank-shaft, and suitable electrical connections, as shown and described.
  4. In an electric railway block-signal, the combination, with a visual signal, an electric motor and suitable gearing for operating the visual signal, the break-wheel *F*, and a spring *f*, pressing on the latter, of the track-instrument consisting of the rock-shaft having arms, as specified, the contact-lever *Q*, the

rod which connects such shaft and lever, a contact-spring *S*, the plain relay *R'*, and suitable electric connections, as specified.

5. In an electric railway block-signal, the combination, with the semaphore, the crank-shaft for operating it, and the break-wheels mounted on the shaft, of the electric motor *M* and gearing that connects it with the crank-shaft, the plain relay, the polarized relay having an insulating-stop, as specified, the switch *C'*, the battery, and suitable electrical connections, as shown and described. 60

6. In an electric railway block-signal, the combination, with the semaphore, a crank-shaft for operating it, and a worm-wheel *C*, mounted on said shaft, of the electric motor *M*, the disk-armature and its sliding shaft, 65 the shaft *I'*, aligned with the sliding shaft, the worm mounted on the latter and engaging said worm-wheel, and the clutch which locks together the aforesaid shafts when the motor is energized, as shown and described. 70

7. In an electric railway block-signal, the combination, with the crank-shaft for operating the signal, of the electric motor *M*, the shaft *I'*, mechanism for connecting these, shafts, the clutch *K* *J*, an electro-magnetic 75 clutch-operating device, the relay adapted to send the current through the motor, and mechanically-operated circuit-breakers, substantially as specified.

8. In an electric railway block-signal, the combination of the electric motor *M*, provided with a sliding armature-shaft, and the circular armature *I*, mounted on the armature-shaft within the field of the motor field-magnet, substantially as specified. 85

9. In an electric railway block-signal, the combination of the signal-operating shaft, the worm-wheel *C*, circuit-breaking wheels mounted on the same, the worm-gear, shaft *I'*, the motor *M*, the armature-shaft, and clutch 90 and spring connections, substantially as shown and described.
